UNITED STATES PATENT OFFICE

JOHN JOSEPH SIPPEL, OF UPPER DARBY, AND WILLIAM F. HENNESSY, OF PHILADELPHIA, PENNSYLVANIA, ASSIGNORS TO THE WICACO MACHINE CORPORATION, OF PHILADELPHIA, PENNSYLVANIA, A CORPORATION OF PENNSYLVANIA

RAYON BLEACHING MACHINE

Application filed September 18, 1930. Serial No. 482,805.

Our invention relates to new and useful improvements in bleaching yarns, and more particularly to the bleaching or treating of rayon.

5 One of the objects of the invention is to provide a machine whereby the yarn in its skein form is caused to travel the length of the machine, so that it may be subjected to the sprays of various chemical solutions, 10 washed and then treated with a water and oil mixture.

Although the present machine is used for bleaching and washing the rayon, it will be understood that other forms of yarns in the textile industry might as well be treated, and it will also be understood that although we have shown, in a partial manner, the various spray pans and pipes, the gist of the invention is the manner in which the skein rods are caused to continuously travel throughout the length of the machine, and to be positively rotated first in one direction and then positively rotated in the other direction, after a short interval of rest.

25 Still another object of the invention is to provide a machine in which the skeins of yarn are carried throughout the various stages of bleaching or washing at a predetermined rate, and positively rotated first in one direction and then the other, and to provide 30 a change gear arrangement whereby the rotation of the skein rods may be changed or regulated to a desired speed.

Still another object of the invention is to 35 provide a bleaching machine wherein two horizontal chains are utilized on the opposite sides of the machine and wherein skein rods are to be placed in special forms of sockets or brackets which will be hereinafter 40 more fully described, so that as the skein rods advance, they will be positively driven or rotated first in one direction, then momentarily freed from rotation, and then will be positively rotated in the other direction.

45 As is well known to those familiar with bleaching machines as used in the textile or rayon industries, it is desirable to have these skein rods rotated in first one direction and then the other, as otherwise the skeins are apt 50 to bunch at one end or the other of the rods,

due mostly to the fact that it is nearly impossible to have the skein rods absolutely level.

Still another object of the invention is to provide a bleaching machine wherein the various pans or sprays will be located above the skein rods, so that the skeins may be subjected in their travel to various solutions, such as sodium sulphide and water, and sodium hypochlorite and an oil mixture or emulsion; and to also provide a continuous travel of the skein rods through the machine positively rotated in first one direction and then the other, and to provide means for regulating the rate of rotation, so that the skeins may be properly treated.

Still another object of the invention is to provide a bleaching machine for longitudinally moving the skein rods, comprising two carrier chains for the skein rods and having a driving socket for an end of each skein rod so that this driving socket will positively rotate its skein rod first in one direction and then in the other, this being accomplished by having a pinion of the drive socket first intermesh with a worm located above the drive socket and then with a worm mounted just below the pinion of the drive socket.

With these and other objects in view, the invention consists in certain new and novel arrangements as will be hereinafter more fully explained and pointed out in the claims.

Referring now to the drawings showing a preferred embodiment,

Fig. 1 is a side elevation of the improved bleaching machine, showing fragmentarily several of the pipes, fittings and the spray pans for the various liquids to be used;

Fig. 2 is a fragmentary top plan view showing one of the skein rods in position and the sockets for another, while parts of the machine are removed for the sake of clearness;

Fig. 3 is a vertical sectional view taken on the line 3-3 of Fig. 1, showing a number of skeins in position on the rod and the manner of driving and rotating the skein rods;

Fig. 4 is a sectional view taken on the line 4-4 of Fig. 3, also showing the manner of rotating the skein rod in first one direction and then the other;

Fig. 5 is an enlarged sectional view taken on the line 5—5 of Fig. 4 showing in dotted lines a change gear arrangement, so that the rotation of the skein rods may be varied;

5 Fig. 6 is a perspective of one of the positive driving sockets for the skein rod and a portion of the link that secures the socket to the chain; and

10 Fig. 7 is a small sectional view of a skein rod taken on the line 7—7 of Fig. 4.

Referring now more particularly to the drawings and for the moment to Fig. 1, there is shown the side elevation of a bleaching machine, which may be of any length desired, 15 and have the necessary spray pipes, valves and pans for bleaching and washing the yarns. That is, any desired form of pumps, pans, sprays and connections for carrying out the bleaching or spraying may be used, as the 20 gist of the present invention is the manner of supporting and conveying and positively rotating the skein rods.

It will be seen that the machine includes a suitable frame 1 with suitable standards 2 25 and the various necessary braces. Near the rear end of the machine there is shown suitably mounted a motor 3, which is belted, as at 4, to the suitably mounted shaft 5, on which there is the main driving worm 6. This 30 driving worm drives the large gear 7 which is mounted on the shaft 8, on which there is also mounted the smaller pinion 9, which in turn meshes with a large gear 10 mounted on the main cross shaft 11, which shaft in turn is 35 supported at its opposite end by the brackets 12.

40 Mounted on one end of this shaft 11 is a small sprocket wheel 12, from which extends the sprocket chain 13 up to the sprocket wheel 14, which wheel is mounted on a small stub shaft 15, while also mounted on this stub shaft 15 is the sprocket wheel 16. In like manner on the other end of the shaft 11 there is a small sprocket 17 which is chained 45 to a sprocket 18 which is mounted on a small stub shaft 19, on which there is also mounted the sprocket 20.

50 Thus it will be seen that when the motor is driven the small cross shaft 11 will likewise be driven, and through the two small sprocket chains, the two small stub shafts with the sprockets 16 and 20 thereon will likewise be driven, which sprockets, as will be shortly mentioned, operate or drive the endless conveyor chains A and B.

At the forward end of the machine, there 60 are the two similar idle chains sprockets, that is, 21 and 22. One of the endless conveyor chains A will extend from the sprocket 20 to the sprocket 22, while a like endless conveyor chain B will extend between the sprockets 16 and 21. Therefore, when the motor is driven, these two chains will travel continuously throughout the length of the 65 machine.

It might be mentioned here that the supports or standards 2 are bolted beneath the side pieces of the frame, as may be seen in Fig. 3, and it is within these respective side pieces of the frame that the upper bights of the chains travel. The standards 2 may be provided with the openings 23, and the lower bights of the chains will pass through these openings within the standards (see Fig. 3).

These endless conveyor chains are made up 75 of a plurality of rollers and links and, as may be seen in Fig. 3, there is also shown mounted in the lower part of the side frames 1 just beneath the respective chains, a small guide or track 24, so that the upper bight of each chain will travel on a guide or track, 80 thus preventing any sag in these upper bights of the chains. This is necessary, because certain worms and pinions come into operation with the sockets carried by the chains to 85 positively rotate the skein rods in first one direction and then the other, as will be shortly mentioned.

Still referring to Fig. 3, it will be noticed that in the bottom walls of the openings 23 90 are respectively bolted the longitudinally extending supports or uprights 25, which extend practically the entire length of the machine and on which, in turn, will rest the little skein rod sockets that are carried by 95 the chains.

Of course, the skein rod sockets are in an inverted position when passing through these spaces in the standards, as they are now on the lower bights of the chains. Thus we have 100 tracks for supporting the upper bights of the chains and uprights for supporting the lower bights of the chains by the now inverted sockets or brackets mounted on the chains.

105 As may be also seen in Fig. 3, the side pieces of the frame 1 are provided with the respective cover plates 26 and 27, while extending downwardly from the inner lower edges of these cover plates on each side of the machine may be seen the guards 28 and 29. Also bolted to the lower edge of the frame on its inner edge may be seen the guards 30 and 31, all four of these guards being preferably made out of lead to prevent the acids 110 from getting into the chains or the mechanisms that are within these side frames. Further guards 31' extend along the machine and adjacent the uprights 25 and are secured to the various standards 2 so that 115 the chain and sockets in the lower bight will be protected from the baths or acids.

120 Thus it will be seen, as far as the description has been set forth, that we have provided endless conveyor chains, the upper bights of which travel in the respective hollow side frames, the inner walls of these said side frames being open so that the skein rods may have their ends passing within these side frames, so that they may travel with the 125

chains, and at the same time the openings of the said side walls are guarded with shields to prevent the acids from splashing into the said side frames and over the parts within 5 the side frames.

Skein rod sockets

Before explaining the positive rotating means for the skein rods S that extend across 10 to the chain in the respective side frame pieces, reference will be made to the little sockets that support the skein rods S, or in other words, the skein rod sockets.

As heretofore mentioned, the chains A and 15 B are made up of rollers, pins and links, that is, each chain is made up of a plurality of rollers 32 through which will fit the ordinary pins 33, as may be seen in Fig. 4, and there is utilized a special form of outside piece 35 20 to form the links of the chains, which piece also acts as a support for the respective sockets to be shortly described.

Referring for the moment to Fig. 6, one 25 of these special outside pieces 35 or connecting links may be seen, which comprises an elongated body with the two holes 36 near its opposite ends, while an integral tongue 37 is shown as extending slightly upwardly and then away from the body portion, which 30 tongue is also provided with the opening 38.

Now referring to Fig. 4 for the moment, 35 it will be seen that this little piece 35, when forming a part of a link, will have the pins 33 extending through the two holes 36. (We 40 have shown two of these side pieces or links in place without the sockets being secured thereto, simply, however, for clearness of illustration. See Fig. 4.)

Thus, it will be seen, we have the two end- 45 less conveyor chains being made up of a plurality of rollers and side pieces, while extending across the top of the links at regular intervals, we have the integral supporting tongues, so that the skein rod sockets may be secured thereto. Of course, ordinary connecting links or side pieces will be used on the inner respective sides of the completed links of the chains.

Now there are two forms of skein rod 50 sockets, one as shown in Fig. 4 (to the right of the drawing) designated by the numeral 40, and the other form 41, as shown to the left of the drawing in Fig. 4.

One form is used for mechanically turning 55 or rotating the skein rods S while the other form is simply to support the other respective ends of the skein rods.

A description of what we term the driving 60 socket 41 is clearly shown in Fig. 6, and will first be described.

It will be understood that a description of 65 one of these sockets 41 will be a description of all of the driver sockets of this type, while a description of the other socket 40 will be a description of all the idle sockets of its type.

Now glancing at Fig. 6, it will be noticed that the socket may be a small casting substantially cubical in shape, and undercut on its bottom surface as at 42, so that when fitting it on the little tongue 37 of the link or sidepiece 35, the front lower edge 43 of the socket will extend down over the front of the tongue 37, to thus make a more rigid structure and prevent the socket from turning. 70

It will also be noticed that this little socket is cored out as at 44 to receive the driving end 45 of a skein rod S. 75

It will be understood that these little sockets of both types are simple castings and 80 may be made up in large cut quantities at relatively small expense.

In the bottom surface of the socket there is provided an opening 46 which is countersunk, (as at 47), to receive a nut 48, (see Fig. 85 4), a bolt 48', in turn passing through the opening 38 of the tongue and secured by the nut 48, thus tightly securing the little socket to the tongue which is, in turn, a part of the link of the conveyor chain A. 90

On the near side of the bracket 41 may be seen the two little rollers 49 which extend slightly above the lower surface of the cut out portion 44, so that the end 45 of the skein rod S when in position will rest on these little 95 steel rollers.

In the front wall of the socket there is mounted a small stub shaft 50 which is squared at its inner end as at 51, so that when the skein rod is resting in position, this 100 little end 51 of the shaft will in turn fit within a receptive pocket 52 formed in the one end of the said skein rod S.

The little stub shaft 50 is also slightly tapered and is provided with a small rim 54 105 while spaced slightly therefrom and at the end thereof is the little pinion or gear 55, leaving the tracking space 53. It is this pinion of the socket that intermittently contacts with two worms that drives the pinion first in 110 one direction and then in the other, as will be shortly set forth.

Reference might be made now to Fig. 3 and to the lower left-hand side thereof, and it will be noticed that the supports 25 fastened 115 within the opening 23 of the standard are of such relative height that the lower bight of the chain will be supported on the one side by one of the supports which extend up to the little rollers 49, while the other portion of the support will form a track that helps support the chain by contacting with the small spaced portion 53 of the shaft 50 in the little 120 socket.

It will thus be seen that these skein rod 125 sockets support the skein rods when the sockets are on the upper bights of the chains, while the sockets in turn when in their inverted position—during their return travel—help support the chains. 125

As may be understood from the several views, these little sockets are fastened at intervals along the conveyor chain A to support the various driven ends of the skein rods, and in a like manner somewhat similar sockets 40 are supported along the conveyor chain B, which sockets are like the sockets just described, with the exception that instead of being provided with the pinions 55 and with the little squared stub ends, they are each simply provided with a small stub shaft 56 with the small tracking flanges 57 at its end.

These little shafts 56 also act as a bearing for supporting the chain when the sockets are in their inverted position, (as shown to the right in Fig. 3), while the little rollers 49 act as a support or bearing for the other sides of the sockets.

In other words, it will be seen that the last socket described is simply an idle socket for holding the respective idle end of its skein rod, while the first socket described is the little driving socket which is to be temporarily interlocked with its respective skein rod.

By forming these little sockets in this manner, not only do they properly support and hold the skein rods, but they also prevent the carrier chains from clanking or rattling or wearing along the lower bights of the chains, as the sockets, although in their inverted positions at this time, cooperate with the longitudinal supports, and thus in reality have a track when on the lower bight of the chains as well as when they travel along the upper bight of the chains.

This support also prevents sagging and stretching of the chain to a great extent, as it will be remembered these conveyor chains are often of great length, and the two sprockets at the opposite ends would in themselves not prevent this sagging.

As far as the specification has proceeded, it will be seen that the skein rods will be manually placed with their one ends in an interlocking position with the driving sockets, while their other ends will rest respectively in the oppositely positioned idle sockets, so that as the skein rods move from the forward to the rear end of the machine, they will extend between the two conveyor chains and after completing their travel, they will be removed by workmen at the rear of the machine.

In their words, the workmen will stand at the forward end of the machine, and fit the drive end of a skein rod into one of the little driving sockets and rest the other end of the skein rod in the opposite socket and thus continuously feed the skein rods to the conveyor chains, while a workman or workmen at the other end of the machine will likewise remove the skein rods, after they have completed their travel and have been sub-

jected to the various sprayings shortly to be mentioned.

By providing the track for the upper bights of the chains, the skein rods will travel in a horizontal plane. This is necessary because the little pinions or gears on the driving sockets are to be intermeshed by staggeredly positioned worms, which will now be described.

Having thus described how the one ends of the chain rods are interlocked in the driving brackets or sockets and the other ends of the chain rods rest in cooperating brackets or sockets, the manner of causing the skein rods in the brackets to turn first in one direction and then in the other will be set forth.

Means for rotating the skein rod

Now it is very desirable that the skein rod not only be carried from one end of the machine to the other, but that they be positively rotated first in one direction and then in the other.

Now referring to Figs. 1 and 5 for the moment, it will be seen that the main cross shaft 11 is also provided with a sprocket 58, from which there extends a chain 59 up to a small standard form of change gear 60, which change gear train comprises the small gear 61 and the larger gear 62 on the same shaft, 95 which in turn meshes with the gear 63, which is movably mounted in the housing 64 there being in turn a smaller gear 65 associated therewith, which meshes with the gear 66, and has the smaller gear 67 meshing with the two gears 68, which gears in turn respectively drive the upper shaft 69 and the lower shaft 70 through the respective bevel gear on their ends. The bracket of this change gear is adjustable so that smaller or larger compensating gears may be fitted in the upper portion to thus change the gear ratio.

This gear change is of the standard type, and is so well known in the art of the mechanics that it needs no further description.

Now the upper shaft 69 is suitably mounted in bearings 69' near its ends, and is intermittently provided with the short worms 71 throughout its length. This shaft 69 will run the entire length of the machine, and as may be seen in Fig. 4, and to the left thereof, is directly above the pinions 55 of the drive sockets, so that after a skein rod is placed in position and moves towards the rear of the machine, the socket pinion 55 will contact 115 with one of these worms 71 and cause the same to revolve and in turn revolve its skein rod, thus driving the skein rod in one direction as long as the pinion contacts with the worm.

Before describing the lower drive shaft 70 and its worms, it will be understood that every time the pinion 55' of the bracket contacts with a worm or mutilated worm on the drive shaft 69, it will revolve and revolve the skein rod.

Now referring to Fig. 5 for the moment, there is shown the worms 72 mounted on the lower drive shaft 70 so that after the pinion 55 has passed from out of contact with the upper worm 71, it will now contact with the lower worm 72, and thus be revolved in the opposite direction.

It will also be noticed that this worm 72, (Fig. 5) does not overlap the worm 71, but is spaced slightly along beyond it, so that temporarily as the skein rods and sockets are being conveyed by the chain, there will be a short interval of time when the respective pinions 55 are not in contact with either of the worms, and during this interval, of course, the skein rods are not revolving.

Also, as may be seen in Fig. 1, the worms on the lower shaft are in staggered relation to the worms on the upper shaft, and this arrangement is carried out throughout the entire length of the machine, which, of course may be anywhere from twenty to fifty feet in length.

Thus, it will be seen that as each skein rod is placed in its driving and idle bracket or socket, and advanced towards the rear of the machine—due to the movement of the conveyor chains—the driving pinions of the sockets will first engage a worm on the upper driving shaft 69, and then engage a worm on the lower driving shaft 70 to thus revolve the skein rods S in the one direction and then in the other, there being intervals of time when the skein rods are not revolving in either direction, to wit, when the respective pinions are not engaged by an upper or lower worm.

In this way all the skein rods as they are fed from one end of the machine will be intermittently rotated in the one direction and then in the reverse direction, and the rate of rotation pre-determined. This rate, however, may be varied to suit by simply placing a different gear in the change gear train, which, of course, will revolve the shafts and respective worms at a greater or lesser speed.

Both shafts 69 and 70 turn in the same direction, but due to the fact that one operates on the teeth at the upper side of the pinion 55 and the other operates on the teeth at the lower side of the pinion 55, the pinion and likewise its skein rod will be caused to travel in one direction and then in the other, even though the two shafts 69 and 70 and their worms, are travelling in the same direction.

Of course, the rate of the travel of the conveyor chains may be pre-determined and varied and likewise the rate of rotation of the skein rods in the two directions may be varied, so that the skeins S' that are placed on the skein rods may be subjected to the various sprays or washes for the desired intervals of time.

As heretofore mentioned, it is desirable to have the skein rods rotate in one direction and

then in the other, first so that they will not all bunch at one end of the skein rods in case the skein rods are not absolutely level, and second so that all parts of the skein on the rods will be subjected to the action of the sprays and baths.

Also by having the rods intermittently stop before rotating first in one direction and then in the other, there is no chance of stripping the teeth on the little pinions 55, nor of stripping the worm gears on the shafts 69 and 70. These shafts are arranged, as may be seen in Fig. 3, within one of the side frame pieces, and are well guarded from the acids in the machine.

As may be seen in Fig. 3, there is provided a large pan 73 located above the skein rods, which has a perforated bottom 74, so that the acids or wash 75 within this pan may be sprayed down over the skeins S, as they travel throughout the length of the machine. Likewise, in Fig. 2, I have shown various pumps 76, and pipes 77, for supplying the liquid material to the pan or pans, and in Fig. 3 there is shown the large pan 78 directly beneath the skein rods, so that the water or liquids may be caught and either used over again or run off to a sewer.

The various inlets and outlets do not form the gist of the invention, and these several parts just referred to are merely for the sake of illustration, and it will be understood that I may use any form of supplying the water or washes or emulsions to the skein as desired.

It will also be seen that the machine may be of any desired length and thereby carry as many skein rods as desired, but the construction and operation will be in no way changed, however.

It is thought that the operation as heretofore set out, is sufficiently clear without reiterating, it being simply necessary to state that the skein rods are carried by sockets on the conveyor chains on the upward bights thereof, and positively driven (or rotated) first in one direction and then in the other direction, there being an intermittent time of no rotation. Now when the skein rods have reached the end of the machine, and the skeins subjected to the various treatments, the rods will be lifted from their places, the skeins removed, and the rods be carried around to the front of the machine, again filled with skeins and subjected to the same travel and treatment.

As may be noticed in Fig. 2, there is a small bracket 83 at the forward end of the machine and to the left of the operator, in which may be rested one end of a skein rod, so that the operator may conveniently support one end of the skein rod while placing the skeins on the rod. Of course, after the rod has been filled with the skeins, it will be placed in the respective sockets on the carrier chain.

To the rear of the machine may be seen the similar bracket 84 but diagonally opposite from 83, so that the rod after leaving the endless conveyor may be likewise conveniently supported at one end, while the workman removes the now treated skeins from the skein rods.

It will also be remembered that the rate of travel of the skein rods can be determined, and that by using the form of change gear for the worm driving shafts, the rate of rotation of the skeins may be predetermined. Likewise, the length of the worms may be such that the skein rods will make any desired number of turns before again idling and then travelling in the reverse direction.

Now the skein rods themselves are preferably cross-like in cross section, and have the little rims 80 at their opposite ends that fit in front of and behind the respective guards 28 to 31 to thus keep the acid from spraying into the side frames. They are also each provided with the marginal ends flanges 81 to limit the number of skeins to be placed on the rod. Of course, one end is provided with a little niche or pocket 52 to fit the squared portion 51 of the shaft 50, as heretofore mentioned.

From the foregoing it will be seen that we have produced a washing and bleaching machine for yarns and preferably for rayon that will permit the rayon skeins to be subjected to the various washing and bleaching actions during their travel through the length of the machine, and at the same time will positively and accurately revolve the skein rods intermittently in opposite directions to thus permit the skeins to be thoroughly acted upon throughout their length and be uniformly treated, and at the same time be prevented from bunching at one end of the skein rod.

Other advantages are obtained, such as simplicity in feeding and simplicity in action, which will be apparent, as an understanding of the invention is had.

We are aware that it is old to frictionally revolve skein rods, but the friction element which is generally rubber, does not wear well, so that the rods are not always revolved. Still in other cases, the rubber is apt to swell, so that the desired rotation cannot be depended upon.

Furthermore, in the friction element, there is no convenient way of changing the rate of rotation, nor pre-determining the number of revolutions that the skein rods will make, whereas in our invention there is an absolute positive rotation of the skein rods, first in one direction and then in the other, and the rate of speed may be varied to suit the conditions.

Many slight changes or modifications might be made in this machine, without in

any way departing from the spirit and scope of the same.

Having thus described my invention, what we claim as new and desire to secure by Letters Patent is:

1. In a machine for washing and bleaching yarns, two laterally spaced conveyor chains, means for operating said chains, receptive means on said chains and adapted to receive skein rods, rotative means on the receptive means that are located on one of said chains, means for rotating the said rotative means of the receptive means which in turn will rotate the skein rods when in position, and the said means also capable of rotating the rotative means intermittently first in one direction and then in the other.

2. In a machine for washing and bleaching yarns, two laterally spaced conveyor chains and means for driving the same, skein rod sockets on said chains and the sockets on one of said chains having rotative means adapted to interlock with skein rod, means adjacent one of said chains to actuate the rotative means of the sockets first in one direction and then in the other direction as the conveyor chains are driven, to thereby rotate the skein rods first in one direction and then in the other.

3. In a machine for washing and bleaching yarns, two laterally spaced conveyor chains and means for driving the same, skein rod sockets on said chains, and the sockets on one of said chains each having a small shaft with a pinion on its end, and the said small shafts adapted to be respectively removably interlocked with skein rods, staggered means above and below the said pinions for intermittently contacting with the said pinions, means for driving said staggered means whereby the said pinions and the skein rods when interlocked therewith will be driven in first one direction and then the other, as the conveyor chains travel along the machine.

4. In a machine for washing and bleaching yarns, two laterally spaced conveyor chains and means for driving the same, skein rod sockets on both chains and the sockets on one chain being idle sockets, and the sockets on the other chain being provided with means that are capable of rotating first in one direction and then the other, and means adjacent these last mentioned sockets for rotating the rotative means of the said sockets, first in one direction and then in the other.

5. In a machine for washing and bleaching rayon skeins, two laterally spaced conveyor chains and means for driving the same, skein rod sockets on both of the said chains, skein rods extending from chain to chain and resting in the said sockets, rotative means on some of the sockets and interlocking with the said skein rods, and means adjacent the rotative means of the sockets to actuate the

same in first one direction and then the other, to thereby likewise actuate the skein rods as they are carried along by the conveyor chains.

5 6. In a machine for washing and bleaching rayon skeins, two laterally spaced conveyors and means for driving the same, driving skein rod sockets on one of said conveyors, and idle skein rod sockets on the other 10 of said conveyors, skein rods extending between said conveyors and fitting within said sockets, interlocking means in the drive skein rod sockets to removably interlock with the respective ends of the skein rods, and means 15 to intermittently contact with the driving skein rod sockets and arranged to positively rotate the interlocked skein rods in first one direction and then the other.

7. In a machine for bleaching rayon, a 20 pair of laterally spaced side frames, an endless carrier in each of said side frames and means for driving the carrier, skein rods rotatably mounted on said carriers and extending between the said side frames, means 25 forming a part of the endless carriers for removably interlocking with said skein rods and means for positively rotating the locking means first in one direction and then in the other to thereby impart a like rotation to 30 the said skein rods.

8. In a machine for bleaching rayon, a pair of laterally spaced side frames, simultaneously movable endless carriers in each of said side frames, skein rod supporting means 35 forming a part of said carriers, skein rods fitting within these supporting means, the supporting means on one of the said carriers having interlocking rotative parts to cooperate with one of the ends of the skein rods, 40 means for intermittently engaging the interlocking rotative parts and so arranged as to positively rotate the said parts and the said skein rods first in one direction and then the other.

45 9. In a bleaching machine a pair of laterally spaced endless carriers and means for simultaneously driving the same, skein rod supporting sockets on said chains, and skein rods fitting within the sockets, one of the 50 sockets for each skein rod being an idle socket, and the other socket for each skein rod being a driving socket rotative means on the respective drive sockets, a plurality of small worms arranged in staggered relation to each 55 other for intermittently engaging the rotative means on the driving socket to thus rotate the skein rods first in one direction and then the other.

10. In a bleaching machine, a pair of laterally spaced endless carriers, and means for simultaneously driving the same, skein rod sockets on one carrier and each of said sockets having a driving pinion adapted to interlock with an end of a skein rod, idle supporting sockets on the other of said carriers,

and a skein rod fitting respectively in a driving and idle socket, two shafts, each provided with worms in staggered relation, and the driving pinion of each driving socket fitting between the two said shafts, and adapted to first contact with the worm on one shaft, and then with the worm on the other, means for driving said shafts to thereby cause the skein rods as they travel to rotate first in one direction and then the other.

11. In a bleaching machine a pair of laterally spaced endless carriers and means for simultaneously driving the same, driving skein rod sockets on the one carrier, and idle supporting sockets on the other of said carriers, skein rods, rotating pinions on the driving sockets and adapted to be removably interlocked with the said skein rods, two series of worms within the path of travel of the pinions of said driving sockets, one series being located above the pinion and one series being located below the pinion, and the worms in one series being in staggered relation to the worms in the other series, and non-overlapping, means for rotating the worms whereby the skein rods will be rotated first in one direction, then idle, and then rotated in the other direction, as they travel along on said carriers.

12. In a bleaching machine, a pair of laterally spaced endless carriers and means for simultaneously driving the same, driving skein rod sockets on the one carrier and idle supporting sockets on the other of said carriers, skein rods, rotating pinions on the driving sockets and adapted to be removably interlocked with the said skein rods, two series of worms within the path of travel of the pinions of said driving sockets, one series being located above the pinion and one series being located below the pinion, and the worms in one series being in staggered relation to the worms in the other series, and non-overlapping, means for rotating the worms whereby the skein rods will be rotated first in one direction, then idle, and then rotated in the other direction, as they travel along on said carriers, and means for changing the rate of rotation of the worms to thereby change the rate of rotation of the skein rods.

13. In a rayon washing and bleaching machine, a plurality of skein rods, means for causing the skein rods to travel throughout the machine, driving sockets on said means for supporting and positively rotating skein rods, worm means for rotating the driving socket, shafts for rotating the worms, and the shafts synchronously connected to the means for causing the skein rod to travel throughout the machine, to provide a positive ratio between the rotation of the skein rods with relation to their rate of longitudinal travel.

14. A socket for supporting and driving the skein rods in a bleaching machine, comprising a cubical formed body, the central portion of which is partly removed, rollers 5 on the inner face of the body and extending slightly above the lower wall of the removed portion, a revolvable stub shaft fitting within the outer face of the socket and having a pinion on its one end and a locking portion 10 on its other end.

15. A driving socket for skein rods comprising a body portion and a chamber open at its top formed in the body portion, rollers extending slightly above the bottom wall of 15 said chamber, a driving shaft fitted within the body portion, one end of the driving member fitting within the said chamber, and the other end of the driving member provided with a small gear wheel.

16. A driving socket for skein rods comprising a body portion and a chamber open at its top formed in the body portion, rollers extending slightly above the bottom wall of 20 said chamber, a driving shaft fitted within the body portion, one end of the driving mem-

ber fitting within the said chamber, and the other end of the driving member provided with a small gear wheel, the bottom portion being partly undercut and a bracket provided with a tongue fitting into said undercut portion. 70

17. A bleaching machine for rayon comprising side frames and standards, endless conveyors in the side frames and means for simultaneously moving the same, means on 75 the conveyors for supporting skein rods, and the said means including means for rotating the skein rods and means for rotating said last-mentioned means, spray pans located above the skein rods and means for pumping liquids thereto, receiving pans beneath the skein rods and lead shields secured to the standards and to the side frames for protecting the conveyor chains from the corrosive action of the liquids. 80

In testimony whereof we affix our signatures.

JOHN JOSEPH SIPPEL.
WILLIAM F. HENNESSY.
